US0D1087975S

(12) **United States Design Patent** (10) Patent No.: **US D1,087,975 S**
Weinberg et al. (45) Date of Patent: ** Aug. 12, 2025

(54) **DISPLAY SCREEN, OR PORTION THEREOF, WITH A GRAPHICAL USER INTERFACE FOR A CHEMISTRY EDUCATION APPLICATION**

(71) Applicant: **TOPHATMONOCLE (US) CORP.**

(72) Inventors: **Justin Weinberg**, New York, NY (US); **Igor Belyayev**, New York, NY (US); **Amanda Kutney**, Atlanta, GA (US); **Sazzad Hossain**, Jamaica, NY (US)

(73) Assignee: **TOPHATMONOCLE (US) CORP.** (CA)

(**) Term: **15 Years**

(21) Appl. No.: **29/787,056**

(22) Filed: **Jun. 3, 2021**

Related U.S. Application Data

(63) Continuation of application No. 17/200,281, filed on Mar. 12, 2021.

CLAIM

The ornamental design for a display screen, or portion thereof, with a graphical user interface for a chemistry education application, as shown and described.

DESCRIPTION

The FIGURE is a front view of a display screen, or portion thereof, with a graphical user interface for a chemistry education application on an electronic device.

The broken lines showing portions of the graphical user interface and display screen form no part of the claimed design.
